STEAM INSTALLATION FOR PRESSING
APPLIANCESFrederick J. Clark, Buffalo, N. Y., assignor to
Eastman Machine Company, Buffalo, N. Y.

Application October 23, 1936, Serial No. 107,213

7 Claims. (Cl. 68—77)

This invention relates to improvements in pressing apparatus of that kind in which a pressing iron or appliance is employed equipped with means whereby steam may be discharged under control, as through perforations in the pressing face of the iron, for the purpose of moistening the goods being pressed, or improving the quality of the work.

Steam pressing irons of this sort are usually heated by means of an electric or other heating element in or on the iron, and they are quite commonly constructed so that the steam which is delivered to the iron from a boiler or other source of supply, is superheated or dried by said heating element before the steam is discharged from the iron, in order to prevent moist steam or condensation from being discharged on the work, and thus possibly injuring or objectionably moistening the goods being pressed.

Control means are provided for shutting off or preventing the discharge of the steam when it is not needed in the pressing of the goods or when the iron is not being used, and for discharging the steam and regulating the quantity discharged, as may be necessary, depending upon the character of the work or of the material being pressed. In some irons, the steam control valve or device is arranged on or adjacent to the iron, but a serious objection to such arrangement of the control valve is that when it is closed to prevent discharge of steam, condensation may occur in the flexible hose or connections which supply the steam to the iron, and it frequently happens when the valve is opened to discharge steam, that the steam superheating means of the iron is not adequate to convert this water of condensation into dry steam so that some water or moisture is discharged from the iron with the result, in many instances, of spotting or injuring the goods being pressed.

Attempts have been made to overcome this objection, by providing steam supply installations for such steam pressing irons in which the valve or device for controlling the discharge of steam from the iron is located in the steam supply pipe above or at a distance from the iron, with the idea of preventing condensation from accumulating in the steam hose or connections to the iron, such control device being operated by a treadle or other operating means conveniently located for actuation by the operator using the iron. However, these installations with distant control devices, as heretofore constructed have not been entirely satisfactory because the constructions or relative arrangements of the con-

trol devices and the steam supply pipes have been such as to form pockets or places in which condensation can collect, with the result that, particularly when the iron is used after it has been standing idle for awhile, this condensation will be blown out by the steam and discharged on the goods being pressed.

The objects of my invention are to provide a steam supply installation with control means for steam discharge pressing appliances which is of a novel construction and arrangement adapted to reliably prevent harmful or objectionable discharge of condensation or moisture from the appliance; in which the control device and the steam supply connections are constructed and arranged so as to eliminate pockets or places in which condensed steam can collect so as to be blown or to pass to the pressing appliance when the control device is operated to discharge steam from the pressing appliance; and also to improve steam installations for steam discharge pressing appliances in the particulars hereinafter described and set forth in the claims.

In the accompanying drawing:

Fig. 1 is an elevation of a pressing apparatus provided with steam supply means embodying my invention.

Fig. 2 is a sectional elevation of the control device, enlarged, on line 2—2, Fig. 1.

Fig. 3 is a sectional elevation of the same on line 3—3, Fig. 2.

Fig. 4 is an elevation, partly in section, illustrating a pressing iron of a type used in apparatus embodying the invention.

10 represents the steam discharge pressing iron of the apparatus. This invention is not concerned with any particular construction of the pressing iron or appliance, which may be a portable hand iron or other pressing appliance of usual or any suitable construction adapted for pressing purposes and to discharge steam under control during the pressing operation. As illustrated in Fig. 4, the iron is provided with an electrical heating element 11 to which electric current is conducted through the usual flexible cord or cable 12, and the pressing face of the iron is provided with perforations 13 through which steam may be discharged to the goods being pressed. The steam may be supplied to the iron through the usual flexible hose or pipe 14 and, as shown, the iron is constructed with one or more passages or chambers 15 with which the hose 14 communicates and which are arranged so that steam passing therethrough to the discharge perforations 13, is superheated or

dried by heat from the heating element 11. The passage or passages 15 may communicate by one or more passages 16 with the discharge perforations 13.

5 The hose or pipe 14 extends downwardly to the pressing iron from an overhead control device 20 to which steam is supplied through an ascending pipe 21. This pipe 21 extends upwardly from a steam and condensation separator 22 interposed between the lower end of the pipe 21 and a steam supply main 23. The steam passes from the supply main 23, through the separator 22 to the pipe 21, and this separator may be of usual or any suitable construction adapted to separate condensation from the steam and permit the condensation to drain off through a steam return or drain pipe 24 leading from the bottom of the separator.

10 The control device 20 preferably comprises a steam cutoff valve, and a regulating valve for regulating the volume of steam which is delivered to the iron for discharge when the cutoff valve is opened. As shown, these two valves are constructed with a single or common valve body 25 which is secured on the upper end of the ascending steam pipe 21, as by screwing the threaded upper end of the pipe into a threaded socket 26 in the valve body. An inlet passage 27 leads upwardly from this socket into a valve chamber 28, in which the movable member 29 of the cutoff valve is located. This member is provided with a suitable valve washer or disk adapted to seat upwardly against and form a stem-tight joint with a valve seat 30 at the upper portion 15 of the chamber 28. The valve disk is normally closed or seated by a suitable spring 31 which, as shown, surrounds the reduced lower portion of the valve member, within a hollow screw cap or plug 32 closing the lower end of the valve chamber 28. The cutoff valve has an operating stem 33 extending out of the valve body through a packing gland 34 for actuation by suitable valve operating means.

15 The regulating valve shown is disposed between the cutoff valve and the descending hose 14 leading from the control device to the pressing iron, and regulates the flow of steam through a passage 35 in the valve body leading from the valve chamber 28 to a nipple or fitting 14a to 20 which the hose 14 is connected. The passage 35 shown is of angle form having a lateral inlet portion connected with the valve chamber 28 above the valve seat 30, and a downwardly extending discharge portion. The regulating valve 25 shown is in the form of a screw needle valve comprising a valve rod 36 having a screw threaded engagement 37 in a bonnet or fitting on the valve body 25 and having a hand wheel 38 at its outer end for turning the valve rod to move its conical inner end toward and from a conical seat 39 in the valve body. By appropriate adjustment of this valve, it may be closed against its seat or set relatively thereto to regulate, as desired, the flow of steam to the iron. In the use of the apparatus, 30 this regulating valve is set to predetermine the desired volume of steam to be supplied to the pressing iron for discharge, and is left in this adjustment during the use of the iron, the steam being turned on to discharge from the iron and shut off to stop the discharge as desired, by opening and closing the control valve 29, which may be opened and closed by suitable operating means.

35 Any suitable operating means for the control valve 29 may be employed, that shown comprising a lever 40 which is pivoted on a bracket 41

fixed on the valve body 25, and is adapted to engage the outer end of the valve stem 33. The lever 40 is connected, as by a rod 42 to a lever 43 which is pivoted on the separator 22, or other suitable support, and is connected, as by a wire 44, to the rock arm of a treadle 45, which is suitably located for operation by the foot of the operator using the pressing iron. A spring 46 connected to the lever 43 normally holds the lever 40 out of engagement with the valve stem 33. By depressing the treadle, the lever 40 is swung to press the stem 33 inwardly and open the control valve 29 against the action of its closing spring 31. Steam is thus delivered to the pressing iron for discharge to the work, and the steam will discharge as long as the valve is held open by depression of the treadle. Upon releasing the treadle, the control valve will be closed by its spring 31 and shut off the steam to prevent its discharge from the iron.

20 It will be noted that the control device 20, comprising the control and regulating valves, is located at the highest point of the steam conduit formed by the ascending pipe 21 and the descending hose 14, through which the steam passes from 25 the separator 22 to the pressing iron; that the pipe 21 extends in an uninterrupted descending direction from the valve body 25 to the separator, and that the flexible hose or connections 14 from the control device to the pressing iron also extends in an uninterrupted descending direction 30 from the valve body 25 to the pressing iron, so that there is no horizontal or ascending portion in the conduit on either the inlet or outlet side of the control device in which steam condensation could collect. Therefore, when the cutoff valve 29 is closed, any condensation occurring in the conduit at the inlet side of the valve can immediately drain back through the pipe 21 into the separator where it will be separated from the steam and discharged, and any steam in the flexible hose or conduit at the outlet side of the cutoff valve will discharge through the hose and pressing iron so as to prevent the formation of condensation in the hose or conduit beyond the 45 control device. Furthermore, it will be noted that the passage 35 in the valve body extends in a descending direction from the regulating valve 36 to its connection with the hose 14, and the seat 30 for the cutoff valve is located above the inlet passage 27 of the valve body connecting the valve chamber 28 with the upper end of the ascending pipe 21. Thus, the only portion of the steam conduit between the separator 22 and the pressing iron which is located at an elevation 50 above the seat 30 of the cutoff valve and in which condensation could collect, is the small, upper end portion of the chamber 28 and the short inlet portion of the passage 35 in the valve body, and these parts are so small that any condensation that might be blown therefrom to the pressing iron by the steam when the valve is again 55 opened after the steam has been shut off, would be of such minute volume that it would be thoroughly vaporized in the steam superheating or drying chamber of the iron. By fixing the valve body 25 at the inclination shown in Fig. 2, even the lateral inlet portion of the passage 35 inclines downwardly from the valve chamber 28, thereby preventing condensation from accumulating in this passage. Any possibility of condensed steam being discharged from the iron is thus effectively prevented.

60 I claim as my invention:

65 1. Steam supply and discharge control means

70 75

- for discharging steam free from condensate from a pressing or analogous appliance constructed for the discharge of steam therefrom, comprising a control device distant from and above said appliance for controlling the discharge of steam from the appliance, a steam supply pipe from a source of steam distant from said appliance ascending to said control device, and a flexible pipe descending from said control device to the appliance, each of said pipes extending in an uninterrupted descent directly from the said control device, whereby condensate is prevented from collecting in said pipes at either side of said control device.
- 10 2. Steam supply and discharge control means for discharging steam free from condensate from a pressing or analogous appliance constructed for the discharge of steam therefrom and having means for heating the steam prior to its discharge, comprising a control device distant from said appliance for controlling the discharge of steam from the appliance, a condensation separator distant from the appliance, a steam supply pipe ascending from said separator to said control device, and a flexible pipe descending from said control device to the appliance, each of said pipes extending throughout its length in an uninterrupted descent directly from the said control device, whereby condensate is prevented from 20 collecting in said pipes at either side of said control device.
- 25 3. Steam supply and discharge control means for discharging steam free from condensate from a pressing or analogous appliance constructed for the discharge of steam therefrom, comprising a valve distant from said appliance for controlling the discharge of steam from the appliance, a steam supply pipe from a source of steam distant from said appliance ascending to said control valve, and a pipe descending from said control valve to the appliance, said control valve having a valve chamber connecting with said pipes and forming therewith a steam supply conduit for the appliance and cooperating members in and 30 controlling the passage of steam through said valve chamber, said conduit extending in an uninterrupted descent from portions of said valve chamber in immediate proximity to both the inlet and outlet sides of said cooperating members in the valve chamber whereby condensate is prevented from collecting in said conduit at either side of said valve.
- 35 4. Steam supply and discharge control means for discharging steam free from condensate from a pressing or analogous appliance constructed for the discharge of steam therefrom and having means for heating the steam prior to its discharge, comprising a valve distant from the appliance for controlling the discharge of steam from the appliance, a condensation separator, a steam supply pipe ascending from said separator to said valve, and a flexible pipe descending from said valve to the appliance, said cut-off valve having a valve member movable relatively to a stationary member in a valve chamber to open and close the valve, said valve chamber connecting with said pipes and forming therewith a steam supply conduit from the separator to the appliance, and said conduit extending in an uninterrupted descent directly from portions of said valve chamber in immediate proximity to both the inlet and outlet sides of said stationary member in the valve chamber, whereby the formation of any pocket in said conduit at either side of said stationary valve member in which condensate can collect and discharge into the conduit is eliminated.
- 40 5. Steam supply and discharge control means for discharging steam free from condensate from a pressing or analogous appliance constructed for the discharge of steam therefrom and having means for heating the steam prior to its discharge, comprising a control device distant from the appliance for controlling the discharge of steam from the appliance, a condensation separator, a steam supply pipe ascending from said separator to said control device, and a flexible pipe descending from said control device to the appliance, said control device comprising a cutoff valve and a regulating valve having a single valve body, one of said pipes extending in an uninterrupted descent directly from said cutoff valve and said other pipe extending in an uninterrupted descent directly from said regulating valve, thereby eliminating any pockets in the conduit formed by said pipes and control device at either side of said valves in which condensate can collect.
- 45 6. Steam supply and discharge control means for discharging steam free from condensate from a pressing or analogous appliance constructed for the discharge of steam therefrom and having means for heating the steam prior to its discharge, comprising a valve distant from the appliance for controlling the discharge of steam from the appliance, a condensation separator, a steam supply pipe ascending from said separator to said control valve, and a flexible pipe descending from said control valve to the appliance, said control valve having a valve member movable relatively to a stationary member in a valve chamber to open and close the valve, said valve chamber connecting with said pipes and forming therewith a steam supply conduit from the separator to the appliance, and said conduit extending in an uninterrupted descent directly from portions of said valve chamber in immediate proximity to both the inlet and outlet sides of said stationary member in the valve chamber, whereby the formation of any pocket in said conduit at either side of said stationary valve member in which condensate can collect and discharge into the conduit is eliminated.
- 50 7. Steam supply and discharge control means for discharging steam free from condensate from a pressing or analogous appliance constructed for the discharge of steam therefrom and having means for heating the steam prior to its discharge, comprising a cut-off valve distant from the appliance for controlling the discharge of steam from the appliance, a condensation separator, a steam supply pipe ascending from said separator to said valve, and a flexible pipe descending from said valve to the appliance, said cut-off valve having a valve member movable relatively to a stationary member in a valve chamber to open and close the valve, said valve chamber connecting with said pipes and forming therewith a steam supply conduit from the separator to the appliance, which conduit extends in an uninterrupted descent directly from said valve chamber in immediate proximity to both the inlet and outlet sides of said stationary valve member, whereby the formation of any pocket in said conduit at either side of said stationary valve member in which condensate can collect and discharge into the conduit is prevented, and a regulating valve controlling said descending conduit between the cut-off valve and the appliance.

FREDERICK J. CLARK.
